ADJUSTABLE SHOE LAST

Arnold Levin, Union City, N. J.

Application December 9, 1939, Serial No. 308,477

2 Claims. (Cl. 12—135)

The present invention relates to shoe lasts and has for its primary object to provide an adjustable last construction adapted to enable a reduction in the length of the last to facilitate the placing of the last in the shoe and in the removal of the last therefrom.

A further object is to provide an adjustable last of this character of simple and practical construction, which is relatively inexpensive to manufacture, easy to manipulate and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view with parts broken away and shown in section.

Figure 2 is a side elevational view showing the last in its retracted position.

Figure 3 is a similar view showing the toe and heel parts separated from each other.

Figure 4 is a fragmentary top plan view of the toe part of the last.

Figure 5 is a front elevational view of the heel part of the last.

Figure 6 is a fragmentary sectional view taken substantially on a line 6—6 of Figure 1.

Figure 7 is a fragmentary sectional view taken substantially on a line 7—7 of Figure 5, and

Figure 8 is a perspective view of the sliding catch member.

Referring now to the drawings in detail, wherein for the purpose of illustration I have disclosed a preferred embodiment of the invention, the numeral 5 designates the toe part of the last, while the numeral 6 designates the heel part thereof. The last is adapted for use in men's, women's and children's shoes, the present embodiment of the invention illustrating the shape of the last designed for use in women's shoes. The toe and heel portions of the last are constructed of separable elements and the rear face of the toe part is inclined upwardly and forwardly as shown at 7, while the front face of the heel part is similarly inclined as shown at 8 to fit flatly against the inclined surface of the toe part.

A longitudinally extending channelled plate 9 is recessed in the inclined rear face of the toe part 7, the channel being secured in position by screws or the like 10 and is provided with a recess shown at 11. Recessed in the inclined face 8 of the heel part is a plate 12 having a longitudinally extending tongue 13 adapted for slidable engagement in the channel 9. As shown in detail in Figure 6 of the drawings, the channel and tongue are provided with interlocking flanges 14

to prevent separation of the parts of the last except when the heel part is moved into its extreme rearmost position.

A portion of the upper surface of the heel part 6 is inclined forwardly and downwardly as shown at 15 and is provided with a dove-tailed groove 16 within which is conformably fitted for sliding movement a latch member 17, the lower end of which is adapted to enter the recess 11 of the toe part 5 to secure the parts against relative sliding movement.

A set screw 18 is threaded through the catch member to secure the same against movement when the parts are in engaged position as shown in Figure 1 of the drawings. The groove 16 is provided with a recess 19 within which a leaf spring 20 is secured at one end, the free end of the spring being positioned in a recess 21 formed in the underside of the catch 17 and engaging the catch to yieldably retract the same from the recess 11 when the set screw 18 is released.

In the operation of the device, when it is desired to place the last in a shoe, or to remove the same therefrom, the catch 17 is withdrawn from the recess 11 and the heel part 6 is moved forwardly along the inclined rear face 7 of the toe part whereby the length of the last is reduced to facilitate the placing of the last into or out of position in the shoe.

It is believed the details of construction and manner of use of the device will be readily understood from the foregoing without further detailed explanation.

What I claim is:

1. A shoe last comprising a toe part and a heel part, means slidably connecting the parts for adjusting the length of the last, said toe part having a recess, a slidable catch carried by the heel part adapted for entering the recess to secure the parts in extended position, spring means for retracting the catch from the recess and releasable retaining means between the catch and the heel part for securing the catch against retracting movement.

2. A shoe last comprising a toe part and a heel part, an interlocking tongue and groove sliding connection between the adjacent edges of the toe and heel parts for adjusting the length of the last, said toe part having a recess, a dove-tail groove in one face of the heel part, a sliding catch conformably fitted in the last named groove having one end engageable in the recess to secure the parts against movement, a recess in the catch, a spring device carried by the heel part and engaging the recess of the slide to retract the same and retaining means carried by the catch and engageably with the heel part to secure the catch against retracting movement.

ARNOLD LEVIN. 60
